UNITED STATES PATENT OFFICE.

REES LITTLETON WHITTINGTON, OF BEDFORD, IOWA.

FENCE.

SPECIFICATION forming part of Letters Patent No. 353,903, dated December 7, 1886.

Application filed April 21, 1886. Serial No. 199,641. (No model.)

To all whom it may concern:

chain it will be seen that when the pickets are

raised out of the links of the lower chain to form a gateway they will be held in the links 55 of the said intermediate chain. When it is

desirable, a wire may be used intermediate of the chains throughout the fence, for the purpose of adding strength to the structure. One 6c

section of this wire is indicated at T, Fig. 1.

In cases where it is desired to connect the fence to confine poultry, the posts are made

longer and long pickets F are employed at

intervals to support a wire or wires, as Q,

to prevent the poultry from flying over the 65

chain. It will be seen that the wire Q, secured to

the post A, extends in a vertical plane from the main fence wire or

links, as shown, and when the fence is 70

raised, the wire Q will press against them in its raised position to stay the fence be-

tween the posts A and B. Provided, also, 75

between the posts A and B, is a wire stay, or

brace, or wire stay, or wire brace, or wire 80

stays, or wire stays, or wire braces, or wire

brace, or wire stay, or wire brace, or wire 85

stays, or wire stays, or wire braces, or wire

brace, or wire stay, or wire brace, or wire 90

stays, or wire stays, or wire braces, or wire

brace, or wire stay, or wire brace, or wire 95

stays, or wire stays, or wire braces, or wire

brace, or wire stay, or wire brace, or wire 100

5 State of Iowa, have invented certain new and useful Improvements in Fences; and I do declare the following to be a full, clear, and exact description of the invention, such as will enable others skilled in the art to which it appertains to make and use the same. Reference is made to the accompanying drawings, and to letters or figures of reference marked thereon, which form a part of this specification.

10 Drawing of a different representation of this invention, and is a side view. Figs. 2, 3, 4, 5. My invention relates to improvements in fences, and particularly to a novel combination of parts, as hereinafter described. Referring to the second accompanying drawing, it is a plan view of a fence, 15 consisting of a series of links, or chains, A, B, C, D, E, F, G, H, I, J, K, K', K'', L, M, N, O, P, Q, R, S, T, U, V, W, X, Y, Z, and the fence stringers, D, of the sections of fence are composed of chains, in the links of which the pickets or palings E E F F G G are inserted.

15 The post A is provided with threaded hook- 30 rods H I J, which rest in seats K K' K'', made through the post from edge to edge, said hook-rods H I J being provided with tightening-nuts L, which are turned up by means of a wrench to stretch the chain stringers and the 35 chain and wire stringers, and also to tighten and loosen them when necessary to provide for contraction under cold and expansion under heat.

20 The links of the chains are tightened around 40 the palings or pickets by compressing the links, except where it is desirable or necessary to provide a gateway or passage for small stock and poultry. At such points the links embrace the pickets loosely, so that the latter 45 may be raised up in the links or lifted therefrom entirely to form the desired passage for small stock and poultry.

25 The chain stringers are arranged one near the upper end and one near the lower ends of 50 the pickets, and where it is desired to form a gateway an intermediate chain is used, as shown at Z. By having this intermediate

As a modification of this wire stay, the wire a is passed through the eye of stake c, and then 85

passed around the picket above the upper link, through which the picket passes, and is

brought down to about the middle of the wire, 90

the lower end being brought up to about the

middle of the wire, and the two ends are tied

by bending them around the wire in any con-

venient manner, preferably, however, as shown.

Staples d are used to secure the links to the pick-

ets at the points where the stays are used, also

at other points where they may be necessary.

The stays hold the chains in such manner as to

cause them to follow the contour of the ground

or to turn a corner at any angle without the

use of posts. The palings or stakes F F, at the

points where the stays or braces come, rest on

cast-metal blocks or feet f, having points g,

which sink. These blocks or feet f prevent

these palings F F from sinking into the ground,

and also prevent them from rotting.

When it is desired to remove the fence from

one location and erect it in another, the fence may be detached from the posts and rolled up in sections and loaded for hauling to such place of erection, where it may be again erected with 5 very little trouble.

Having described this invention, what I claim, and desire to secure by Letters Patent, is—

The combination, with the fence-post and the 10 stretcher-post connected by chain stringers, of the chain and wire stringer intermediate of the

upper and lower stringer, the stationary pickets, and the stay-wires provided with securing stakes, and the movable pickets resting in alternate links of the upper, lower, and intermediate stringers, substantially as specified. 15

In testimony whereof I affix my signature in presence of two witnesses.

REES LITTLETON WHITTINGTON.
